COLLAPSIBLE CASE

Giorgio Armenia, Rome, Italy

Application February 6, 1947, Serial No. 726,883
In Italy August 27, 1946

1 Claim. (Cl. 217—15)

1

The object of the present invention is to provide a collapsible case which, when not in use, may be folded up so as to occupy only a very restricted space.

All the various parts of the case are connected by hinges and the relative operations of opening up and folding up the case are thus rendered particularly simple and easy.

The invention is illustrated in the attached drawing, in which

Fig. 1 is a perspective view of the case when folded;

Fig. 2 is a perspective view of the case of Fig. 1 when partially opened up;

Fig. 3 is a perspective view of the case of Fig. 1 when completely unfolded and assembled for use;

Fig. 4 is a fragmentary view in perspective of one of the hinged joints between the lid and the back wall of the case; and

Fig. 5 is a fragmentary view in perspective of the hinged joint between the lid and the back wall after the lid has been folded against the back wall and showing means for supporting the lid in a vertical opened position.

Referring to the drawing, it will be understood that the case is built up substantially of a bottom 1, two side walls 2 and 3 and two ends 4 and a lid 5.

The side 2 forms the front of the case and is connected to the bottom 1 by means of hinges 31 mounted on the outer edges of a short side panel 32 which is rigidly fixed to the bottom 1. The hinge 31 comprises merely a pin 33 passing through a hole in one end of the L-shaped brace 33a which is screwed to the edge of the panel 32 and the edge of the bottom 1. Thus the front 2 can fold along a line L which is spaced from the bottom by a distance equal to thickness of the other folded parts as shown in Fig. 1.

The side 2 is also provided with two grooves 6 adapted to receive the ridges 7 mounted on the edges of the end walls 4. The top edge of the front side 2 is reinforced on the inside with a beam 8 which extends along the whole length of the top edge and which engages the lid 5 when the case is collapsed. The top outer corners of the side 2 are provided with hinged clasps each comprising a short arm 20 having a pivotal connection 21 to the side 2, a hinge 22 positioned at the top edge, and a long arm 23 having a hole 24 therein adapted to engage a pin 25 mounted on the outer edges of the top 5. This clasp can pivot around the connection 21 so that the hole 24 can also engage a pin 26 on

2

the outer edge of the base 1 as shown in Fig. 1. The length of the arm 23 is substantially equal to the total thickness of the folded case as shown in Fig. 1.

5 The side wall 3 forming the back of the case is hinged to the bottom 1 by the same type of hinge as used for connecting the front 2 to the panel 32, namely by means of a pin 35 passing through a hole in an L-shaped member 36 which 10 is screwed or fixed to the base 1. Like the side wall 2 the inside edges of the wall 3 is provided with grooves adapted to receive the ridges 7 on the end walls 4. On the top edge 40 of the side 3 are mounted two stops 16 which are pivotally mounted on the pin 41 to the inside of the side 3 and are adapted to be rotated through 15 90° to the vertical position shown in Fig. 5 so that the top 5 will rest against this stop while the case is being filled. This latter position is 20 shown in broken lines in Fig. 5.

The ends are hinged to the inside of the bottom 1 and may be lowered as shown in Fig. 2 to lie inside the bottom. The upper edges 9 of the end walls 4 are adapted to fit into slots 10 25 formed between the upstanding ridge 43 and the side framing 44 of the inside of the lid 5 as shown in Fig. 2.

As shown in Figs. 4 and 5, the lid 5 is hinged to the top edge of the side wall 3 by means of 30 double jointed hinges 25 which permit the lid 5 to swing from the closed position of Fig. 4 through an angle of 275° to lie against the side 3 as shown in Fig. 5.

The folding of the case is carried out easily. 35 The lid 5 is turned over to lie on the outer face of the side 3. The end walls 4 are then folded to lie on the inside face of the bottom 1; the side wall 3 and lid 5 are then folded over on top of the flattened end walls 4. Finally the side 40 wall 2 is turned over the lid 5. The arm 23 of the clasp 11 is then rotated through an angle of 90° and bent downward to seat the pin 26 in the hole 24 of the arm 23. The case will now be completely folded and ready for carrying by 45 means of the handle 45 which is fixed to the outside of the panel 32, as shown in Fig. 1. Thus it is seen that the same clasp 11 which is used to maintain the lid closed when the case is assembled for use as in Fig. 3 is also utilized for maintaining the case in the folded condition as shown in Fig. 1.

The invention has been described in detail above by way of example and not by way of limiting the invention. It is understood that the invention may undergo structural alterations

within the skill of the art without transcending the scope of the invention which is indicated in the appended claim.

What I claim is:

In a collapsible case, the combination of a bottom, end walls hinged only to the bottom and adapted to fold inwardly and rest flat upon the bottom, a side wall hinged to the bottom and having a top panel hinged to its upper edge, said side wall and top adapted to fold flat upon the 10 flattened end walls, a side wall hinged along a line spaced from the bottom edge by the thickness of the other folded parts, and locking means pivotally mounted at the top of said last-mentioned side, said means being hinged to lock the lid in place when the case is assembled and adapted to be rotated through 90 degrees to lock the folded parts to said bottom when the case 15 is folded.
